SINK FAUCET SHELL

Stephen A. Young, Delphi, Ind.

Application June 23, 1949, Serial No. 3,467

Term of patent 14 years

(Cl. D91—3)

To all whom it may concern:

Be it known that I, Stephen A. Young, a citizen of the United States, residing at Delphi, in the county of Carroll and State of Indiana, have invented a new, original, and ornamental Design for a Sink Faucet Shell, of which the following is a specification, reference being had to the accompanying drawings, forming part thereof.

In the drawings Fig. 1 is a top plan view of the sink faucet shell showing my new design; Fig. 2 is a front elevation thereof and Fig. 3 is a side elevation thereof.

I claim:

The ornamental design for a sink faucet shell, substantially as shown.

STEPHEN A. YOUNG.
